UNITED STATES PATENT OFFICE.

WILLIAM DEMUTH, OF NEW YORK, N. Y.

DESIGN FOR A PIPE MOUTH-PIECE.

SPECIFICATION forming part of Design No. 13,049, dated July 18, 1882.

Application filed May 24, 1882. Term of patent 7 years.

To all whom it may concern:

Be it known that I, WILLIAM DEMUTH, a citizen of the United States, residing at New York, in the county and State of New York, have invented and produced a new and original Design for the Mouth-Piece of a Smoking-Pipe, of which the following is a specification.

This design consists in a mouth-piece emanating from a musk-melon-shaped globe, which is interposed between two fillets, a concave colareno, and a torus interposed between a fillet and a plinth.

The accompanying drawing represents a side view of my design.

In this drawing, the letter A designates a curved mouth-piece, which emanates from a musk-melon-shaped globe, a, that is situated between a fillet, b, above and another fillet, b', beneath. Below the fillet b' is a concave colareno, c, which is separated by a fillet, d, from a torus, e, resting upon the plinth f.

The principal feature of my design, however,

is the musk-melon-shaped globe a, which imparts to the mouth-piece a novel and ornamental appearance.

What I claim as new, and desire to secure by Letters Patent, is—

1. The design for the mouth-piece of a smoking-pipe, consisting of the mouth-piece A and the musk-melon-shaped globe a, as shown and described.

2. The design for the mouth-piece of a smoking-pipe, consisting of the curved mouth-piece A, the musk-melon-shaped globe a, the fillets b b', the concave colareno c, the fillet d, the torus e, and the plinth f.

In testimony whereof I have hereunto set my hand and seal in the presence of two subscribing witnesses.

WM. DEMUTH. [L. S.]
